(57) **CLAIM**

What is claimed is the ornamental design for a address light, as shown and described.

DESCRIPTION

FIG. 1 is a perspective view of an address light, showing the new design;

FIG. 2 is a front elevational view thereof;

FIG. 3 is a rear elevational view thereof;

FIG. 4 is a right-side elevational view thereof, the left-side elevational view being a mirror image thereof; and,

FIG. 5 is a top plan view thereof; the bottom view being a mirror image thereof.

The broken lines showing a numeral in FIG. 1 are included for the purpose of illustrating the invention in use, and form no part of the claimed design. All other broken lines represent features which form no part of the claimed design.
